UNITED STATES PATENT OFFICE.

GEORGE A. KNAAK, OF MILWAUKEE, WISCONSIN.

PRESSURE MEMBER.

1,385,378.

Specification of Letters Patent. Patented July 26, 1921.

Application filed April 9, 1919. Serial No. 288,850.

To all whom it may concern:

Be it known that I, GEORGE A. KNAAK, a citizen of the United States, residing at Milwaukee, in the county of Milwaukee and 5 State of Wisconsin, have invented certain new and useful Improvements in Pressure Members, of which the following is a specification, reference being had to the accompanying drawing, forming a part thereof.

10 This invention relates to pressure members and the object of the invention is to improve the construction of pressure members in the manner to be hereinafter described and claimed.

15 Referring to the drawings which accompany this specification and form a part hereof, which drawings illustrate an embodiment of this invention, and on which drawings the same reference characters are used to designate the same parts wherever they may appear in each of the views, Figure 1 is an elevation of the pressure member, looking in the direction of the arrow on Fig. 2, parts being shown in section and parts being 20 shown as broken away; and Fig. 2 is a vertical section, taken on the line 2—2 on Fig. 1, looking in the direction indicated by the arrows.

Referring to the drawings, the reference 30 numerals 1 and 2 designate the two sides of a pressure member box 3. The sides 1 and 2 are made from any suitable metal and are provided with corrugations as clearly shown by Fig. 2 of the drawings. Preferably the 35 corrugations are concentrically arranged in the well-known manner and the sides 1 and 2 are provided with flanges 4 and 5. Heretofore it has been customary to solder the flanges 4 and 5 together and rely upon the 40 corrugations to give the sides of the box flexibility so that the sides could bulge out and in with variations of pressure. The result, however, has been that more or less of the movement of the sides has been transmitted 45 to and taken place at the edges 6 and 7 where the sides are turned to form the flanges 4 and 5 and the continued bending of the metal at these edges has resulted in breakage. The principal object of this invention is to dispense with an edge which 50 can be subjected to bending movements. I accomplish this result by holding the sides 1 and 2 in such a manner that all of the movements of the sides must be confined 55 within the sides themselves.

In the construction illustrated by the

drawings, the ordinary flanges 4 and 5 are shown united by solder 8 and clamp members 9 and 10 bear against the sides 1 and 2 to prevent motion being transmitted to the 60 edges 6 and 7. When a flanged construction is used for the box, I place a rigid bearing member 11 between the two sides of the box against which the two sides can be firmly secured. The clamp members 9 and 10 may 65 be secured in any suitable manner as, for example, by bolts 12 and should have curved or flaring surfaces 13 and 14 so that the sides will not have to bend over sharp edges. The sides of the box are substantially tangent to 70 the curved surfaces 13 and 14 of the clamp members 9 and 10, when the box is not bulged outwardly, and, as the sides of the box are bulged outwardly they assume new positions of substantial tangency with more remote parts of the curved surfaces of the clamp members. The result is that the metal of the sides is constrained to move in predetermined elongated arcs and pinch points, 75 or sharp bends are obviated.

The box 3 is illustrated as provided with two apertures into one of which projects a nipple 15 and into the other of which projects a stud 16. The nipple 15 is provided with a bore 17 and is illustrated as secured 80 in a boss 18 to which a pipe may be connected to permit fluid entering the box 3. Pressure plates 19 and 20 are assembled upon the nipple 15 and the stud 16 to back the sides 1 and 2 and to provide for uniform 85 bulging of the box 3 and spacing washers 21 and 22 are interposed between the pressure plates and the sides 1 and 2. Nuts 23 and 24 are screwed upon the reduced, screw threaded ends of the nipple 15 and the stud 16 hold 90 the parts firmly together and solder is preferably used to make the joints tight. The reference numeral 25 designates a lever to 95 which the pressure member can transmit its movements to perform some desired work 100 and this lever is mounted in a case 26 which is provided with a removable cover 27 to which the pressure member is secured. This construction makes the stud 16 a floating member which can move away from or toward the nipple 15 as the pressure varies in the box 3. It will be understood that the lever 25 is acted upon by some resistance as a spring, not shown, which tends to press the arm 28 of the lever against the stud 16. 105

It will be readily understood that in assembling the pressure member, the sides 1

and 2, the pressure plates 19 and 20, the spacing washers 21 and 22 and the nuts 23 and 24 are first assembled with the nipple 15 and the stud 16 and the joints are soldered. The bearing member 11 is then placed between the sides 1 and 2 and the solder 8 applied to make a tight joint. The clamping members 9 and 10 are then applied, and the pressure member is then ready for use in the construction illustrated by the drawings or with any other apparatus with which it may be used.

What is claimed is:

1. The combination in a pressure member, of a bearing member, a corrugated metal side, and a clamp member to clamp said side against said bearing member, said clamp member being provided with a curved surface and the side being substantially tangent to said curved surface and adapted to bend over the same to more remote points of substantial tangency.
2. The combination in a pressure member, of a bearing member, two corrugated metal sides, clamping members to clamp said sides against said bearing member, said clamping members being provided with curved surfaces and the sides being substantially

tangent to said curved surfaces and adapted to bend over the same to more remote points of substantial tangency.

3. The combination in a pressure member, of a nipple, a stud, pressure plates secured thereto, a box composed of corrugated metal sides provided with flanges secured to the nipple and to the stud, a rigid bearing member inside the box adjacent said flanges, and clamping members to clamp said sides against said bearing member and provided with curved surfaces, the sides being substantially tangent to said curved surfaces and adapted to bend over the same to more remote points of substantial tangency.

4. The combination in a pressure member, of a bearing member, a yieldable metal side, and a clamp member to clamp said side against said bearing member, said clamp member being provided with a curved surface and the side being substantially tangent to said curved surface and adapted to bend over the same to more remote points of substantial tangency.

In witness whereof I hereto affix my signature.

GEORGE A. KNAAK.
